US0D1113863S

(12) **United States Design Patent** (10) Patent No.: **US D1,113,863 S**
(45) Date of Patent: ** Feb. 17, 2026

(54) **EARPHONE**

(71) Applicant: **SHENZHEN SHOKZ CO., LTD.**,
Guangdong (CN)

(72) Inventors: **Lei Zhong**, Shenzhen (CN); **Zeteng Yan**, Shenzhen (CN); **Sunjie Huang**, Shenzhen (CN); **Haochen Liu**, Shenzhen (CN); **Haofeng Zhang**, Shenzhen (CN); **Jiang Xu**, Shenzhen (CN); **Zeying Zheng**, Shenzhen (CN)

(73) Assignee: **SHENZHEN SHOKZ CO., LTD.**,
Shenzhen (CN)

(**) Term: **15 Years**

(21) Appl. No.: **29/995,266**

(22) Filed: **Mar. 25, 2025**

Related U.S. Application Data

(62) Division of application No. 35/520,303, filed on Mar. 15, 2023 (U.S. filing date under 35 U.S.C. 384), and having an international filing date of Mar. 15, 2023.
